CLAIM

(21) Appl. No.: **29/517,407**

The ornamental design for a filter having a bottom anchor flap to cause sediment deposition around a storm sewer inlet, as shown and described.

(22) Filed: **Feb. 12, 2015**

DESCRIPTION

(51) **LOC (10) Cl. 23-01**

FIG. 1 is a perspective view of a filter having a bottom anchor flap to cause sediment deposition around a storm sewer inlet showing my new design;

(52) **U.S. Cl.**

FIG. 2 is a side view thereof;

USPC **D23/209**

FIG. 3 is a top view thereof;

(58) **Field of Classification Search**

FIG. 4 is a bottom view thereof; and,

USPC D23/207, 209; 210/170.03, 499, 747.3,
210/747.2, 747.4

FIG. 5 is an cross-sectional view taken generally on the line
5-5 of FIG. 3.

See application file for complete search history.

The cross-line pattern, which is partially shown for ease of
illustration, represents a conventional fabric and is under-
stood to repeat uniformly throughout the indicated area.
